(57) **CLAIM**

The ornamental design for a watering connector, as shown and described.

DESCRIPTION

FIG. 1 is a perspective view of our watering connector according to our new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top view thereof; and,

FIG. 7 is a bottom plan view thereof.

The perspective view of FIG. 1 shows an interior of the watering connector that is rotationally symmetric as shown in FIG. 2.
